PAPER CONTROL FOR TYPE-WRITING MACHINES.

1,244,011.

Specification of Letters Patent.

Patented Oct. 23, 1917.

Application filed January 31, 1917. Serial No. 145,580.

To all whom it may concern:

Be it known that I, NILS H. ANDERSON, a citizen of the United States, residing at Bridgeport, in the county of Fairfield and 5 State of Connecticut, have invented a new and useful Improvement in Paper Controls for Type-Writing Machines, of which the following is a specification.

This invention relates to the mechanism of 10 typewriting machines which holds the paper to the platen.

When a large number of copies are being made at one time or when the paper is comparatively thick and stiff, or when envelopes 15 or cards are being put through a typewriting machine, the paper as it comes around the platen tends to stand up or assume a tangential position with relation to the surface of the cylindrical platen, and under 20 such conditions when the type strike there is considerable noise and the impression is more or less imperfect.

The object of this invention is to provide means which can be readily attached to 25 many of the present makes of typewriting machines and that is particularly serviceable for use in connection with single keyboard machines, that is, those machines in which the platen is raised and lowered for the different characters, which means will cause 30 the paper being printed upon to follow around and closely hug the periphery of the platen and thus insure a firm backing with a consequent elimination of noise and an insurance of better impression of the type.

The invention is illustrated in connection with a typewriting machine of the "Underwood" make. Figure 1 shows a plan, with portions broken away, of such a typewriting 40 machine provided with a paper holding means which embodies this invention. Fig. 2 shows on larger scale a section of the platen with paper passing about it and held down to its periphery by one form of holder 45 which embodies this invention. Fig. 3 shows a front elevation of the machine, with parts broken away, so as to expose the paper holder. Fig. 4 shows a top view of a modified form of holder. Fig. 5 shows a front 50 elevation, and Fig. 6 shows an edge elevation of the same in the position occupied when holding paper to the surface of a platen.

In the class of machine illustrated the 55 platen 1 is mounted on the paper carriage 2

in such manner that it is rotated when the carriage is returned after having been fed across the machine and is lifted when the shift keys 3 are depressed in order to change from one set of characters to the other by 60 the well known mechanism. The platen is as usual also rotatable independently of the keys for turning in and setting the paper by the hand wheels 4.

For causing the paper 5 to follow around 65 the periphery and closely hug the platen, no matter how many thicknesses there are or how stiff the paper is, a curved spring finger 6 is provided. This spring finger conforms substantially to the surface of the platen 70 and its upper end tends to bear down thereon quite a distance above as well as at about the horizontal diameter of the platen. This spring finger is formed at the upper end of and projects from a yoke 7 which desirably 75 has outwardly extending fingers 8 that are shaped to bear against the platen at about its horizontal diameter. The lower ends of the yoke are fastened to rods 9 that extend forwardly and somewhat outwardly toward 80 the sides and that have their front ends fastened to collars 10 which are fixed on a shaft 11. This shaft extends horizontally across the machine frame near the front and at each end is journaled in the upper end of a 85 bracket 12 which is fastened to the top of the frame 13 near the front by a screw 14. A spring 15 which is wound about the shaft near one end has one end engaged with a bracket 12 and has the other end engaged 90 with one of the rods 9 in such manner as to tend to force down the holder so that the spring finger will bind the paper to the surface of the platen and yet will rise as the platen is lifted by the shift key. A latch 16 95 is pivoted to the shaft 11 near one end in such manner that when very heavy cards or envelopes are put into the machine the holder may be locked against the platen by swinging the latch around into engagement with 100 the front edge of the bracket 12 to which it is adjacent.

In the form of holder above described the lower ends of the yoke are fixedly attached to the inner ends of the supporting rods. 105 If it is desired the yoke may be pivotally connected with the supporting rods as illustrated in Figs. 4, 5 and 6. In this form the lower ends of the yoke 17 may be loosely mounted on studs 18 which pass through 110

holes in the ends of the supporting rods 19. In this case it is desirable to wind springs 20 about the studs and have one end of each spring engaged with the end of the yoke, 5 and the other end of each spring engaged with the supporting rod, in such manner as to bend to throw the yoke with its vertical pressure finger 21 and horizontal pressure fingers 22 against the surface of the platen 10 or such sheets of paper as are passed around the platen.

This device holds the paper regardless of the number of sheets or the stiffness of the paper close to the surface of the platen 15 whether the platen is in its lowest or highest position, without interfering with the free up and down movements of the platen, and it holds the sheets being written on around the surface of the platen so that they have 20 a solid backing, which insures good impressions and a minimum amount of noise. The yoke which supports the holding fingers straddles the ribbon carrier and the type guide and does not interfere with the striking 25 of the type against the paper at the desired spot. The yoke supporting rods extend forward and sidewise so as not to interfere with the movements of the type levers, and the brackets which support the 30 shaft that carries the wires are attached to the frame at the front where the attaching means can be easily manipulated. The resistance or pressure of the holder can be increased by locking it down when desirable.

35 The invention claimed is;

1. The combination with the frame and platen of a typewriting machine, of brackets attached to the frame, a shaft journaled in said brackets, rods extending from said 40 shaft, a yoke attached to said rods, a finger projecting from the yoke, and a spring on said shaft and arranged to cause the finger to bear upon the platen.

2. The combination with the frame and 45 platen of a typewriting machine, of brackets attached to the frame near the front, a shaft journaled in said brackets, rods extending rearwardly from said shaft, a yoke attached to said rods, a finger projecting from the yoke, and a spring on said shaft 50 and arranged to cause the finger to bear down upon the platen.

3. The combination with the frame and

platens of a typewriting machine, of brackets attached to the frame, a shaft journaled in said brackets, rods extending from said shaft, a yoke pivotally attached to said rods, a finger projecting from the yoke, and springs arranged to cause the finger to bear 55 upon the platen.

4. The combination with the frame and platen of a typewriting machine, of brackets attached to the frame, a shaft journaled in said brackets, rods extending from said shaft, a yoke attached to said rods, a finger 60 projecting from the yoke, a spring on said shaft and arranged to cause the finger to bear down upon the platen, and a latch on the shaft and arranged to engage one of the brackets for locking the finger down upon 70 the platen.

5. The combination with the frame and platen of a typewriting machine, of brackets removably attached to the frame near 75 the front, a shaft journaled in said brackets, rods extending rearwardly from said shaft, a spring on said shaft and arranged to force the rods downwardly, a yoke pivotally attached to said rods, springs at the pivotal connections of the rods and yoke 80 and arranged to force the yoke rearwardly, and fingers projecting from the yoke.

6. The combination with the frame and platen of a typewriting machine, of brackets removably attached to the frame near 85 the front, a shaft journaled in said brackets, rods extending rearwardly from said shaft, a spring on said shaft and arranged to force the rods downwardly, a yoke pivotally attached to said rods, springs at the 90 pivotal connections of the rods and yoke and arranged to force the yoke rearwardly, fingers projecting from the yoke, and a latch on the shaft and arranged to engage one of the brackets for locking the fingers down 95 upon the platen.

7. The combination with the frame and platen of a typewriting machine, of brackets attached to the frame, a shaft journaled in said brackets, rods extending from said shaft, a yoke attached to said rods, a finger projecting from the yoke, and a spring arranged to cause the finger to bear down 100 upon the platen.

NILS H. ANDERSON.
